(57) **CLAIM**

(**) Term: **15 Years**

The ornamental design for a vehicle front center bumper cover, as shown and described.

(21) Appl. No.: **29/632,630**

DESCRIPTION

(22) Filed: **Jan. 9, 2018**

FIG. 1 is a front elevational view of a vehicle front center bumper cover, showing our new design;

(51) LOC (11) Cl. **12-16**

FIG. 2 is a left side elevational view thereof;

(52) U.S. Cl.

FIG. 3 is a right side elevational view thereof;

USPC **D12/169**

FIG. 4 is a top plan view thereof;

(58) **Field of Classification Search**

FIG. 5 is a bottom plan view thereof;

USPC D12/169, 196, 86, 90-92; 293/102, 113,
293/115, 117, 120; 296/180.1, 180.2

FIG. 6 is a top, front, and left side perspective view thereof;

CPC B60R 19/02; B60R 19/04; B62D 25/08
See application file for complete search history.

and,

FIG. 7 is a bottom, front, and left side perspective view thereof.

Any broken lines represent an internal boundary of the design; the line itself and the area within form no part of the claim.
